UNITED STATES PATENT OFFICE.

LEROY LEGGETT, OF SIDNEY, IOWA.

CISTERNS OR WELL CLEANER.

SPECIFICATION forming part of Letters Patent No. 794,806, dated July 18, 1905.

Application filed April 26, 1904. Serial No. 205,023.

To all whom it may concern:

Be it known that I, LEROY LEGGETT, a citizen of the United States of America, residing at Sidney, in the county of Fremont and 5 State of Iowa, have invented a new and useful Cistern or Well Cleaner, of which the following is a specification.

The object of my invention is to provide means for readily and effectively cleaning 10 dirt and sediment from wells and cisterns without stirring up the mud and diffusing it throughout said well or cistern.

My invention consists in the construction, arrangement, and combination of elements 15 hereinafter set forth, pointed out in my claims, and illustrated by the accompanying drawings, in which—

Figure 1 is a perspective illustrating my device in folded or collapsed condition adapt- 20 ed to be inserted in a well or cistern. Fig. 2 is a perspective, partly in section, showing my device as required for practical use. Fig. 3 is an enlarged detail view of portions of my device. Fig. 4 is a bottom plan of the de- 25 vice. Fig. 5 is a vertical section of the lower portion of the device.

In the construction of the device as shown the numeral 10 designates an ingress-pipe, which is formed with a valve-seat 27 in its 30 upper end.

The numeral 11 designates an egress or discharge pipe, and bolts 30 connect the pipe 11 to the pipe 10, so that the lower open end portion of the egress-pipe is located between 35 the ends and on the periphery of the inlet-pipe. A screen 25 is mounted rigidly on the inlet-pipe 10 and surrounds the lower end portion of the egress-pipe 11; but the open upper end portion of the inlet-pipe is outside 40 said screen. A bracket 13 is mounted on and fixed to the pipes 10 11 and is formed with sliding bearings adapted to receive the valve-rod 12, mounted for reciprocation therein. A valve 14 is mounted on the lower 45 end portion of the rod 12 and normally en- gages the valve-seat 27 of the pipe 10. A tank 10^a is provided and is formed with a hopper-bottom with a circular aperture in its apex in which the inlet-pipe 10 is mount- 50 ed. A lock-nut 9 is mounted on the lower

end portion of the inlet-pipe 10 and serves to connect said pipe and the hopper-bottom of the tank 10^a rigidly yet removably, the screen 25 limiting movement of the pipe and tank relative to each other in one direction 55 in opposition to said nut. The tank 10^a is provided with a removable and replaceable cover 22, and said cover is formed with an aperture 32, through which the upper portion of the egress-pipe 11 extends. A pump- 60 pipe or well-tube 28 is connected to the upper end portion of the egress-pipe 11 by a coupling 31. Another aperture 23 is formed in the cover 22, and the valve-rod 12 extends through said aperture and is provided with 65 an air-valve 15, adapted to close said aperture at times. A cord 20 is fixed to and rises from the valve-rod 12 and is adapted for manual actuation to lift said rod and the valves 14 15 thereon. A spring 26 is mount- 70 ed on and tends to depress the valve-rod 12 to seat the valve 14 on the upper end portion 27 of the pipe 10. A box 6 is pivotally mounted on the lower end portion of the inlet-pipe 10, and a box 5 is pivoted to the 75 first box. A head 4 is fixed to the box 5 by bolts or screws 34, and said bolts or screws extend below the lower face of said head and form feet to support the head above the bottom of a well or cistern. The head 4 80 preferably has sixteen equal plane faces on margin, and flanges 24, preferably made of sheet metal, are fixed to and depend from said faces. Arms 16, preferably formed of spring-wire and looped at their central portions, are hinged by said looped central portions to margin portions of the head 4 and extend after the manner of umbrella-ribs from said head and may be oscillated by draft applied to cords 19. Eyes 17 are 85 formed on the arms 16 and are connected in series by draft devices, such as chains 18, to draft-cords 19 19, which draft-cords extend upwardly and are adapted for manual actuation to open or permit the folding of the arms. 90 The outer ends of the arms 16 are turned up-ward, and a textile cover 29, preferably of canvas or sail-cloth, is mounted on and fixed at its center to the head 4 and at its outer upturned margin to the upturned outer ends 100

- of the arms 16. Cords 35 and 36 are stitched to the cover 29 in such manner as to stiffen said cover against undesirable collapse and hold the outer edge or margin of said cover 5 upturned to prevent the upper surface thereof becoming loaded with mud and sediment, the latter cords being below and parallel with the arms 16 to form a waterway underneath the umbrella-base. A valve-seat 8 is formed 10 in the head 4 and is controlled by a gravity-operating check-valve 7, hinged to said head, to break the suction of the umbrella from the bottom of a cistern.

In practical operation the parts are assembled as shown in Fig. 1 and lowered into a well or cistern, and after entering the water in said well or cistern the umbrella-base is opened or expanded into the position shown in Fig. 2 by draft applied to the cords 19 19. 15 20 While descending into the water in the well or cistern air escapes from and water enters the umbrella-base through the seat-aperture 8 beneath the check-valve 7, and water also passes through the pipe 10 into tank 10^a to 25 sink the device. When the device has been properly positioned in the well or cistern, with the bolts or screws 34 resting on the bottom or as near the bottom as the mud and sediment will permit, draft is applied to 30 the cord 20 to lift the valve 14 from the seat 27, whereupon mud, sediment, and dirty water flows through the inlet-pipe 10 into the tank 10^a and fills said tank and the lower portion of the pipe 11. A pump is then applied to the tube 28 and operated to suck the 35 dirty water, mud, and sediment through the pipe 11 to a suitable place of discharge, the screen 25 being of such mesh as to permit the passage of mud and sediment, but holding 40 back the trash in the tank 10^a to be emptied

on the removal of the device from the well or cistern, thus avoiding clogging of the pump employed. The valve 14 may be left elevated from the seat 27 in order to pump mud and dirty water from the bottom of the well or 45 cistern beneath the umbrella-base, or it may be closed until the tank 10^a is emptied by pumping and reopened to permit refilling of the tank by pressure-flow from beneath the umbrella-base. 50

On the removal of the device from a well or cistern it should be cleaned by unscrewing the nut 9 from the pipe 10 and the coupling 31 from the pipe 11 and then lifting the cover 22 and pipes out of the tank. 55

I claim as my invention—

1. A well or cistern cleaner, comprising a tank, ingress and egress pipes communicating with said tank, a screen over the communication between said egress-pipe and the 60 tank, a valve adapted for manual control and governing the communication between said ingress-pipe and tank, and a collapsible umbrella device mounted below said tank.

2. A well or cistern cleaner, comprising a 65 flexible, foldable, collapsible umbrella device, formed with an opening at the center thereof, an ingress - pipe communicating through said opening, a tank communicating with said ingress-pipe, an egress-pipe leading from said tank, a valve controlling the ingress-pipe and a screen covering the communication between the egress-pipe and tank. 70

In testimony that I claim the foregoing as my own I have hereto affixed my signature 75 in the presence of two witnesses.

LERoy LEGGETT.
